DUST INDICATOR FOR AIR-METHOD
CLEANING SYSTEMS

Daniel Benson Replogle, Berkeley, Calif.; Bank of America National Trust and Savings Association, Carl S. Replogle, Harold E. Queen, and Laurie H. Bullock, executors of said Daniel Benson Replogle, deceased, assignors to The Ohio Citizens Trust Company, Toledo, Ohio, a corporation of Ohio, as trustee

Application October 8, 1941, Serial No. 414,212

8 Claims. (Cl. 302—65)

The invention relates to dust indicator for air method cleaning systems and the subject matter of the present application is related to that of my prior applications Ser. No. 381,200 filed Feb. 28, 1941, now Patent No. 2,269,483, dated January 13, 1942; Ser. No. 387,717, filed Apr. 9, 1941; Ser. No. 395,320 filed May 26, 1941; Ser. No. 411,931 filed Sept. 22, 1941, now Patent No. 2,293,920, dated August 25, 1942, and of my application Ser. No. 412,861, filed Sept. 29, 1941, entitled Dust ar- resting indicator for suction cleaners.

The present device is adapted to connect with the suction pipe of a suction cleaning system and consists of two principal elements: (1) a pipe-coupling element having a trough-shaped socket adapted to receive a transparent globular element, and (2) the transparent globular element adapted to be placed into the coupling element and readily removable therefrom, and in a position providing communication through the pipes coupled.

In accordance with the herein disclosed embodiment of the invention the transparency is composed of two like saucer-shaped discs and a flat perforated disc interposed between the two so as to form an oblate spheroid. Coincident edges may be fused together if made of glass or in any suitable way secured around the periphery if made of other material, as Celluloid or methyl-methacrylate, vinyl esters and the like.

The invention will be more readily understood by reference to the accompanying drawings in which is set forth an illustrative embodiment of the inventive thought, it being understood that the invention in its broadest aspects is not limited to the details of construction.

A form of the full sized article is illustrated. In the drawings:

Fig. 1 is a side view taken at right angles to the oblate spheroid when placed in position for service and showing the coupling element in an angular position with the entrance and exit nipples shown in partial perspective.

Fig. 2 is a view of the assembled article taken at right angles to that of Fig. 1.

Fig. 3 is a top view of the device with parts broken away.

Fig. 4 is a diagrammatic view suggestive of the position of the device in the pipe line of a clean- ing system.

Fig. 5 is a diagrammatic view suggestive of the removal by hand of the globular element.

Figure 6 is a diagrammatic side view of the globular element.

Fig. 7 is an exploded view taken edgewise of the article in Fig. 6.

Fig. 8 is a side view of the coupling element.

Fig. 9 is a view taken at right angles of Fig. 8 in exploded form.

Figs. 10 and 11 are designed to show the device when viewed at right angles to the plane of the pipe line instead of at right angles to the plane of the oblate spheroid or globular part, Fig. 11 being of the coupling element only with the globular part removed.

Referring to the drawings and with particular reference to Fig. 4, A denotes a hollow wand or suction pipe of an air-method cleaning system having a suitable floor tool or nozzle B at one end thereof. C denotes a coupling element having means for yieldingly and releasably supporting a transparent globular element D therein. The coupling element or fitting C communicates at its entrance end with the suction pipe A and at its exit end with an outlet pipe E, preferably a flexible tube, which communicates with a suitable source of suction not shown. The globular element D is provided with apertures which are aligned with the inlet and outlet pipes of the coupling element respectively.

The coupling element C may be constructed of two similar halves 1 and 1', the part designated 1 carrying the entrance pipe 2, and the part designated 1' carrying the exit pipe 3. The parts are secured together by rivets or otherwise as at 4, 5 or 6, and extending heads of the rivets may have helically coiled about them wire detents 7 and 8 which are designed to hold the globular part D in position by tension against its edges and engagement in notches at opposite edges of the globular element D, said notches being designated 7' and 8' respectively.

The transparent globular element D is preferably formed of two halves 20, 21, of any suitable transparent material such as glass, Celluloid or one of the newer transparent synthetic resins. The halves may be fused together at their meeting edges as indicated at 22 or may be secured together in any suitable manner. These halves include between them a suitable flat disc or dia- phragm 9 which may be formed of the same trans- parent material as the halves 20 and 21 of the globular member D. The disc 9 may be of one piece or may be formed of a plurality of lamina- tions as set forth in my prior applications.

The diaphragm or disc 9 may be provided at its middle with a screen area 10 which may be perforated through the transparent material of the disc 9 or a wire screen may be inserted and

secured between two laminations of the diaphragm transparent material 9.

A designating arrow 23 is shown to indicate the part of the diaphragm or assembled globular part D which should be uppermost when in use so that apertures 11, 11 in the lower wall portions of the shells 20, 21 will register with the entrance and exit pipes respectively.

The operation of the device may now be readily understood. During the sweeping operation dust is drawn in through the pipe section 2, entering through aperture 11, and striking the diaphragm 9 is whirled in a counter-clockwise direction on the hither side of the diaphragm, the heavier particles of dust continuing to whirl around the annular area and being visible to the eye. The stream of air helixes through the screen and exits at the opposite side. Should dust which is too large, or in particles, or lint, gather on the screen, the globular element may be grasped by the hand, pulled out from between the retention springs 7 and 8, and turned about 180 degrees to present the reverse side, and reinserted in its place. The stream then passing through the screen in the opposite direction clears it of its obstruction while the moving air continues in the same direction through the pipes.

It is obvious that articles of value may be arrested in this way instead of being carried into the dust receptacle of the sweeping system, and the articles may be dumped out of the globular element through the port 11 which may receive the same on either side depending on which side is placed to receive, toward pipe 2.

In case a diaphragm is preferred in which there is simply a round opening instead of a screen, a separate element may be assembled and used in the coupling part which need not be changed for that purpose.

The plane of the diaphragm 9 should be oblique to the plane of the entering and exit pipes which are about 120 degrees with each other.

The invention has been set forth in detail for the purpose of illustration but it will be obvious that numerous variations and modifications may be resorted to without departing from the spirit of the invention.

What I claim is:

1. In a suction cleaning system, a dust indicator comprising a coupling element having entrance and exit pipes at diagonally opposite sides of a central receiving trough; and a transparent globular dust indicating member shaped to conform to said trough and releasably and yieldingly supported therein, said transparent member having a pair of apertures communicating with the inlet and outlet pipes respectively of said coupling element.

2. A dust indicator as set forth in claim 1, wherein the dust indicating member is composed of two dish shaped halves, with an apertured disc included between them.

3. A suction cleaning system as set forth in claim 1 wherein the coupling element is provided with detent devices adapted to engage the pe-

riphery of the dust indicating member for yieldingly holding the same in position.

4. A suction cleaning system as set forth in claim 1 wherein the dust indicating member is an oblate spheroid shaped transparent element having a boundary rib around its greatest circumference adapted to fit into a bottom groove formed in the trough of said coupling.

5. A dust indicator for suction pipes comprising a coupling element having entrance and exit pipes at diagonally opposite sides of a central receiving trough, an oblate spheroid shaped transparent dust indicating element having a boundary rib around its greatest circumference adapted to fit into a bottom groove of the trough of the coupling element and having in its transparent sides apertures adapted to register respectively with the entrance and exit pipes aforesaid, said transparent dust indicating element being adapted to be lifted out and replaced within the coupling element and to be retained therein by holding devices engaging with the periphery thereof.

6. A dust indicator for a suction cleaning system comprising a coupling element including a trough portion and angularly disposed inlet and exit pipes connected to opposite sides of the trough; and a transparent globular element having a peripheral portion shaped to fit within the trough and having a central diaphragm member, said transparent element having separate apertures on opposite sides of said diaphragm adapted to communicate with the inlet and the outlet pipe respectively of said coupling element, and coacting means carried by the coupling element and said transparent element respectively for positioning the transparent element within the trough with said aperture in registry with said inlet and outlet pipes.

7. A dust indicator for suction pipes comprising a coupling element having inlet and outlet pipes at diagonally opposite sides of a central receiving trough, a transparent dust indicating globular element having a peripheral portion shaped to fit within said trough, and having spaced apertures adapted to register respectively with said inlet and outlet pipes, said transparent dust indicating element being adapted to be lifted out and replaced within the coupling element, and to be retained therein with the said apertures in registry with the inlet and outlet pipes by coacting means carried by said coupling element and transparent element respectively.

8. A dust indicator for suction pipes comprising a coupling element including a central receiving trough having inlet and outlet pipes extending diagonally from opposite sides thereof, and a transparent dust indicating member adapted to be seated in said trough, said member being in the form of an oblate spheroid having a central apertured diaphragm, and having in its transparent sides a pair of apertures adapted to register with inlet and outlet pipes respectively when the dust indicator member is positioned within the trough.

DANIEL BENSON REPLOGLE.
